UNITED STATES PATENT OFFICE.

RAY P. JACKSON, OF EDGEWOOD PARK, PENNSYLVANIA, ASSIGNOR TO WESTINGHOUSE ELECTRIC & MANUFACTURING COMPANY, A CORPORATION OF PENNSYLVANIA.

METHOD OF AND MEANS FOR COATING INNER SURFACES OF HOLLOW BODIES.

Application filed June 4, 1923. Serial No. 643,143.

My invention relates to a method of, and means for coating the inner surfaces of hollow bodies and particularly to providing a perimetral band of coating material on 5 the inner surface of a recessed insulator adjacent to the mouth of the recess.

One object of my invention is to provide a method and means of the above indicated character that shall facilitate and economize 10 the manufacture of hollow bodies, such as insulators of the plural-part nested type in which it is desired to coat the inner surfaces thereof in a certain manner.

Another object of my invention is to provide 15 a method of, and means for, applying a uniform coating of material to the inner surface of a body adjacent to the entrance of the body.

While my invention may be employed in 20 connection with hollow bodies of various characters, sizes and materials, an immediate application thereof is in connection with an insulating member having recesses for the reception of a similar insulating member to 25 which it is to be attached.

The formerly employed methods of coating the inner surfaces of hollow bodies by dipping and by applying coating material with a brush are inadequate for the purpose 30 for which my invention is intended. For example, in dipping a hollow body to coat its inner surface, the outer surface will be coated also and in applying a brush, the material must be such as will readily lend 35 itself to application thereby. Further, in employing a brush, the hollow body must be large enough to admit the same, and, sometimes, the hand of the operator.

To apply the coating material to an exact 40 limiting line on the inside surface only of a hollow body, is not possible by dipping, because, as pointed out above, the outside of the body will be coated also, and in employing a brush, the operation is impractical 45 or requires great skill, depending upon the size of the opening. The so-called "air brush" is also subject to limitations which render it insufficient for my purposes.

Assume a hollow body which it is desired 50 to coat, on its inside surface only, to an exact inner perimetral line some distance from the mouth of the hollow body. One of

the members of a plural-part insulator of the nested type is such a body. In connecting the nested portions of an insulator, it 55 is usual to employ a cement that is subjected to deterioration by moisture. To seal the exposed edges of the cement, it is desirable to employ a gum in the form of perimetral bands that are placed on the respective parts 60 before the steaming operation, which causes the bands to come together in a homogeneous mass. This construction is fully shown and described in a copending application of N. A. Wahlberg, Serial No. 633,721 filed April 65 21, 1923, for insulators, and assigned to the Westinghouse Electric & Manufacturing Company.

One of the members has a portion of inverted substantially cup-shape having a uniform band of gummy material on its inner surface adjacent to its mouth. This material does not lend itself to ready application with a brush.

In practicing my invention, I provide 75 means for causing a coating liquid to enter a hollow body in volume or bulk. The liquid is controlled to enter the body to a predetermined exact position or inner perimetral line and to be withdrawn from the 80 body to provide a uniform band of coating material on the inner surface of the body.

Figure 1, of the accompanying drawings, is a side view, partially in elevation and partially in section of a device for effecting 85 the method of my invention, showing the parts in the position assumed before the coating operation, and

Fig. 2 is a view similar to Fig. 1, showing the coating liquid raised to its inner limiting position in the hollow body.

In general, a device for practicing the method of my invention may comprise a receptacle or tank 1 for containing a body of coating liquid 2, a lid member 3 for the 95 receptacle 1 and which constitutes a supporting means for a hollow body 4 that is shown as one unit of a plural part insulator, a tubular member 5 for communication between the interior of the body 4 and a 100 vacuum pump (not shown) and a valve 6 in the tubular member 5.

The receptacle 1 may be of any suitable construction for the reception of one, or

more, members 4. The member 4, in this instance being a unit of a plural-part insulator, is provided with a petticoat portion 7, which is adapted to rest on the member 3. 5 A depending portion 8, of inverted substantially cup shape and having a recess 9, extends through an opening 14 in the member 3.

Ordinarily, the level of the liquid 2 is so 10 adjusted that the surface of the liquid barely touches the mouth of the recess 9. However, the lower edge of the portion 8 may be immersed in the liquid 2, depending on how 15 far above the lower end of the member 4 it is desired to have the liquid engage the outer surface thereof.

The tubular member 5 is supported in a side wall of the receptacle 1, as by a bushing 10, and is connected, through the valve 6, to 20 a vacuum pump having constant operating conditions. The valve 6 is preferably of the two-way type having a passage 11 therein for connecting the recess 9 to the source of vacuum and a passage 12 for connecting the 25 recess 9 to the atmosphere.

In operation, the vacuum pump is adjusted to a valve which, when the valve 6 is in the position shown in Fig. 2, will cause the liquid to rise to a predetermined level. 30 Initially, and as shown in Fig. 1, the member 4 is placed through the opening 4 in the member 3 to the position shown, in which position, the lower end of the member 4 is in engagement with the surface of the liquid 2. 35 With the valve 6 in the position shown in Fig. 1, the recess 9 communicates directly with the atmosphere and the level of the liquid 2 in the recess is thereby unaffected.

By turning the valve 6 to the position 40 shown in Fig. 2, the vacuum pump is connected to the recess 9 in which the liquid rises to the level shown. To avoid disturbing the liquid level such as would occur if the member 4 were to be lifted away from the member 3 while the level of the liquid 45 were as shown in Fig. 2, the valve 6 is turned back to the position shown in Fig. 1. This action admits air pressure to the recess 9 and causes the level of the liquid to recede 50 gradually, thus leaving a smooth perimetral band of coating material around the inner surface of the member 4 adjacent to the mouth of the recess 9.

Various modifications of my invention, 55 such as having the tubular member 5 communicate only with the atmosphere and in protecting the outer surface of the portion 8, while the liquid is caused to enter the recess, will be apparent, and I desire that all 60 such modifications be included in the scope of my invention, as set forth in the appended claims.

I claim as my invention:

1. A device for coating the inner surface 65 of a recessed member comprising a recep-

tacle for a coating liquid over which the member is placed with an entrance to said recess adjacent to the surface of the liquid and a tubular member connecting the recess to a vacuum producing means. 70

2. A device for coating the inner surface of a member having a recess of substantially cup shape comprising a receptacle for a coating liquid, means for supporting the member with the cup inverted and the mouth of the 75 cup adjacent to the surface of the liquid, a tubular member extending between the interior of the cup and a vacuum producing means and a two-way valve in the tubular member for alternately connecting the cup to 80 said vacuum producing means and to the atmosphere.

3. The combination with an insulator having a recess of substantially cup-shape, of 85 means for applying a coating liquid in the form of a perimetral band on the inner surface of the cup, adjacent to its mouth, comprising a receptacle for the coating liquid, means for supporting the insulator with the cup inverted and the mouth of the cup en- 90 gaging the surface of the liquid, a tubular member connected between the interior of the cup and a vacuum producing means adjusted to a constant value in accordance with the desired width of said coating band, and 95 means for controlling the rise and fall of the liquid in the cup.

4. A device for coating the inner surface of a recessed member comprising a receptacle for a coating liquid over which the member is placed with an entrance to said recess adjacent to the surface of the liquid and means including a tubular member extending between the exterior and the interior 100 of the recess for controlling the liquid level 105 in the recess by fluid pressure.

5. A device for coating the inner surface of an insulator having a recess of substantially cup-shape, and a petticoat intermediate its ends, comprising a receptacle for a coating liquid, means engaging said petticoat for supporting the insulator with the cup inverted and the mouth thereof sealed by the coating liquid, and means including 110 a tubular member extending between the interior and the exterior of the cup for causing the liquid to rise and fall in the cup by fluid-pressure changes in the cup. 115

6. A device for coating the inner surface of an insulator having a recess of substantially cup shape and a petticoat intermediate its ends, comprising a receptacle for a coating liquid, a cover member for said receptacle having an opening providing a support for said petticoat whereby the insulator is positioned with the cup inverted and the mouth of the cup sealed by the liquid, and means including a tubular member extending between the interior of the cup and the exterior of the receptacle for causing the 125 130

liquid to rise and fall in the cup by fluid-pressure changes in the cup.

7. The method of coating the interior surface only of a member of substantially cup-shape having imperforate walls, comprising placing the mouth of the cup in inverted position over a body of coating liquid so that

the liquid seals said mouth and in withdrawing air from the cup.

In testimony whereof, I have hereunto ¹⁰ subscribed my name this 24th day of May, 1923.

RAY P. JACKSON.
